UNITED STATES PATENT OFFICE.

FRANK M. FABER, OF PITTSBURG, PENNSYLVANIA, ASSIGNOR TO
WILLIAM S. ELLIOTT, OF PITTSBURG, PENNSYLVANIA.

TURBINE.

SPECIFICATION forming part of Letters Patent No. 792,975, dated June 20, 1905.

Application filed October 12, 1903. Serial No. 176,665.

To all whom it may concern:

Be it known that I, FRANK M. FABER, of Pittsburgh, Allegheny county, Pennsylvania, have invented a new and useful Turbine, of which the following is a full, clear, and exact description, reference being had to the accompanying drawings, forming part of this specification, in which—

Figure 1 is a longitudinal vertical section 10 of my improved turbine. Fig. 2 is an end view showing one of the clamping-rings. Figs. 3 and 4 are detail views.

My invention relates to the class of turbines, and more particularly to the turbines employed in connection with boiler-cleaners; and the object of the invention is to improve the structure of the turbine, to provide an efficient thrust-bearing therefor, to prevent water from creeping into the bearing, and to 20 lengthen the life of the tool.

In the drawings, 2 is the turbine-case, of cylindrical form, with a hose-coupling 3 screwed to its rear end.

4 is the turbine-wheel proper, having curved 25 passages 5 cut through it, these passages being closed at the outer sides by the metal of the wheel. The wheel is cut away around its intermediate part to form an annular chamber 6 between the hub portion 7 and the outer 30 ring portion containing the passages 5. The hub portion 7 is internally screw-threaded to receive an externally-screw-threaded bushing 8, forming a bearing around the turbine-shaft 9. The hub is provided with a rearwardly- 35 projecting sleeve portion 10, which is provided on its exterior surface with helical or inclined grooves, as shown, and the inner enlarged bore of this sleeve portion 10 receives the rear annular ring portion 11 of the bush- 40 ing 8. This ring portion 11 fits loosely within the bore of the sleeve 10 and is provided with a transverse slot 12, which receives the inwardly-projecting lugs 13 of a ring 14, surrounding the shaft 9. The ring 14 is beveled 45 or inclined on its rear annular face to receive a conical thrust-ring 15. A series of these rings are fitted against each other in the chamber within the sleeve portion 10 and around the shaft, and at the rear end of the nest of

conical disks or rings is a ring 16, having an 50 inclined inner face and provided on its rear face with projecting lugs 17, fitting in a slot within the stationary portion 18 of the turbines. This stationary portion is secured within the casing and contains the passages 55 or guides 19, leading to the curved passages or vanes in the rotary wheel portion. The front end of this stationary portion 18 is recessed to inclose the portion 10 of the wheel and is provided with an inner annular ring 60 portion 20, entering the chamber 6 and having an undercut or inwardly-beveled outer face 21. The shaft 9 is screw-threaded in its rear portion and engages screw-threads in a hole leading through the stationary portion 65 18. The rear end of the shaft is secured by the lock-nuts 22.

The bushing 8 is slotted at its front end to receive lugs on the ring 23, which is similar to the ring 16. A series of conical thrust- 70 rings 24 fit between the ring 23 and the beveled inner face of a collar 25 on the shaft 9. Around the forwardly-projecting portion 26 of the shaft is a sleeve 27, having an enlarged rear portion 28 screwed into the wheel around 75 the forward thrust-bearing. The head 29 for the tool is screwed onto the front end of the sleeve 27, which at its front end contains a screw - cap 30, covering the chamber 31, through which the end of the shaft 26 may 80 be reached. This end of the shaft is provided with a notch 32 to receive a screw-driver in securing the parts together.

In the operation of the device the water or fluid under pressure enters the chamber 33 in 85 the rear part of the case and thence flows through the passages 19 and into the curved passages 5 to rotate the turbine-wheel. Any leakage between the stationary part of the turbine and its wheel passes into the chamber 90 6 and is thrown to the outer wall of this chamber by the undercut portion of the ring 21. Any water passing back over the hub 7 is forced out into the chamber 6 by the vanes or grooves of the part 10, and the water in the 95 chamber 6 flows out through the leakage-holes 34. The shaft 9 remains stationary and the turbine-wheel rotates on the bearing between

the bushing 8 and the shaft 9 and also on the bearing between the sleeve 27 and the portion 26 of the shaft. The end thrust in both directions is taken up by the conical thrust-rings, which make the device long-lived. These conical thrust-rings present an important advantage in that they do not slide over each other and wear rapidly, as in the case of flat thrust-rings. Their form causes them to nest within each other and be retained in place.

10 The advantages of my invention result from the peculiar arrangement of the bearing, from the arrangement of the leakage-chamber, the elongation of the journal, and the long life of 15 the turbine under the severe surface of driving a cleaner-head.

The shaft may rotate with the wheel or the wheel may rotate on the shaft, and many other changes may be made in the form and 20 arrangement of the parts without departing from my invention.

25 The leakage-chamber, provided with leakage-holes, disclosed in the present application constitutes the subject-matter of certain claims in my copending application, Serial No. 147,068, filed March 10, 1903.

I claim—

30 1. The combination of a shaft carrying an annular seat, a turbine-wheel revoluble on said shaft and provided with an annular seat, and a series of rings between said seats, loose on said shaft, and having conical faces in contact across their surfaces; substantially as described.

35 2. The combination of a shaft carrying an annular seat, a turbine-wheel revoluble on said shaft and provided with an annular seat, a series of dished rings between said seats, loose on said shaft, and in contact across their surfaces, and a casing extending from said wheel over said rings; substantially as described.

40 3. The combination of a shaft having two spaced annular seats, a turbine-wheel revoluble on said shaft and provided with corresponding annular seats, and a series of dished rings between each pair of opposed seats, loose

on said shaft, and in contact across their surfaces; substantially as described.

4. The combination of a shaft having two spaced annular seats, a turbine-wheel revoluble on said shaft and provided with corresponding annular seats, a series of dished rings therefor between each pair of opposed seats, loose on said shaft, and in contact across their surfaces, and a casing extending from the wheel over each set of rings; substantially as described.

5. The combination of a shaft carrying an annular seat, a turbine-wheel, a bushing in said wheel provided with a shaft-bearing and an annular seat, and a series of dished rings between said seats, loose on said shaft, and in contact across their surfaces; substantially as described.

6. A turbine-wheel having a leakage-chamber and inclined projections or threads arranged to force the water forwardly out of said chamber; substantially as described.

7. A turbine having a rotary turbine-wheel with an inner leakage-chamber and a stationary ring or deflector projecting into the chamber; substantially as described.

8. A turbine-wheel arranged to rotate around a fixed shaft, separated thrust-bearings between the turbine and shaft and a collar secured to the wheel and surrounding a front portion of the shaft forming a bearing for said wheel; substantially as described.

9. A turbine-wheel having a shaft provided with a thrust-bearing, and journals for said wheel on both sides of the thrust-bearing; substantially as described.

10. A turbine-wheel having two separated thrust-bearings and journals, one of said journals being between the thrust-bearings; substantially as described.

In testimony whereof I have hereunto set my hand.

FRANK M. FABER.
